UNITED STATES PATENT OFFICE.

WILLIAM E. BURKE, OF LORAIN, OHIO, ASSIGNOR OF ONE-HALF TO CHARLES F. ROSCH, OF LORAIN, OHIO; MARY ROSCH ADMINISTRATRIX OF SAID CHARLES F. ROSCH, DECEASED.

VALVE FOR FLUSHING-TANKS.

1,114,444.

Specification of Letters Patent.

Patented Oct. 20, 1914.

Application filed January 21, 1913. Serial No. 743,406.

To all whom it may concern:

Be it known that I, WILLIAM E. BURKE, a citizen of the United States, residing at Lorain, in the county of Lorain and State 5 of Ohio, have invented new and useful Improvements in Valves for Flushing-Tanks, of which the following is a specification:

The present invention has reference to flushing tanks and like apparatus wherein 10 the main or inlet valve is operated by a fluid-controlled device which is ordinarily in the form of a float-lever.

It proposes, briefly, improved means for imparting a positive initial movement in 15 one direction, to assist the action of the float-lever and thus insure the certainty and rapidity of operation of the apparatus.

An embodiment of the invention is illustrated in the accompanying drawing, where- 20 of:

Figure 1 is a vertical sectional view showing the said invention applied to a flushing tank; Figs. 2 and 3 are enlarged longitudinal sectional views showing the valve in 25 open and closed position, respectively; and Fig. 4 is a transverse section taken on the line 4-4 of Fig. 2.

In said drawing, 5 indicates, generally, a flushing tank of ordinary construction, furnished with the usual inlet and overflow 30 pipes 6 and 7. The inlet pipe is equipped with a controlling device 8, here shown as in the form of a bib, whose inlet portion 9 is fitted directly upon the end of said pipe. 35 The cylindrical body portion 10 of said bib constitutes a casing whose inner wall is provided with left-hand screw-threads 11 and is further provided with a longitudinal slot 12, the inner end of said slot producing a 40 shoulder 13.

At the inner end of the casing is located the valve seat 14, which latter is formed in the usual partition 15 and serves as the means of connection between the aforesaid 45 inlet 9 and the outlet or discharge spout 16. The valve 17, which co-operates with said seat, is carried by the stem 18 and is formed with an externally-threaded enlarged portion 19 that engages the casing threads 11. 50 Said stem projects through a central opening in the usual cap 20 fitted on the body portion or casing 10, and has connected thereto one end of the lever 21, the latter carrying at its other end a suitable float 22.

55 The movements of the afore-mentioned

float-lever 21 are imparted directly to the valve stem 18, as will be understood, and the latter, on being rotated, will thus seat or unseat the valve. In the arrangement illustrated in Fig. 1, the float-lever will normally be held in raised position by the water in the tank, flushing of the tank causing the lever to drop and thus rotate the valve stem in a clockwise direction, Fig. 4, with the result that the valve is unseated. As it frequently happens that the movement of the valve away from its seat is produced only with some little difficulty, owing to the threaded portion thereof binding in the corresponding portion of the bore of the casing, means is provided for imparting a positive initial movement to the valve away from its seat, when the flushing operation takes place. The means for producing this initial movement is here shown as constituted by an expandable coil spring 23 which encircles the valve stem and bears at one end against the shoulder 13 produced by the formation of the slot 12, into which slot the end in question extends, as depicted in Figs. 2 and 3. The other end of the spring is bent laterally and inserted into an opening 24 formed transversely through the valve stem. In consequence of this arrangement, the aforesaid spring will be normally compressed, owing to the normally raised position of the float-lever, but as soon as the latter starts to drop, the spring will immediately expand and thus rotate the valve stem clockwise, thus loosening the threaded portion 19 of the valve in the threaded portion of the bore and moving the valve a slight distance away from its seat. Continued clockwise rotation of the valve stem incidental to the dropping of the float-lever will move the valve the required distance away from its seat, as will be understood, thus opening communication between the inlet and discharge portions 9 and 16 of the bib and permitting the water to flow through 90 said portions into the tank.

In order to prevent splashing of the water thus discharged through the bib spout, the latter may be expanded at two portions remote from each other, as indicated by the numerals 25, 25, the portion intermediate these expanded portions, and also the extreme end of the spout being contracted, as indicated by the numerals 26, 26. In this way the water will be caused to flow with 105 110

less force into the tank. The bib may further be provided with a vertical pipe 27 whose lower end fits in the bore of a lug or boss 28 that is constructed upon the spout 5 and opens into the latter, the upper portion of the pipe being formed with a crook that projects downwardly into the overflow pipe 7. The water flowing through this pipe 27 into the overflow pipe serves to reseal the 10 bowl, as will be understood.

I claim:—

1. The combination, with a valve casing having an internal valve seat and an interiorly-threaded bore leading to said seat and 15 provided with a longitudinal slot; of a valve threaded in said bore and provided with a stem; an operating lever connected to said stem; and a normally compressed spring having one end engaged in said slot and the 20 other end connected to said stem, and tending to rotate the latter in one direction, to unseat said valve.

2. The combination, with a flushing tank

and its water-inlet pipe; of a bib attached to the end of said pipe and having its body 25 portion constituting a valve casing, the inner wall of which is threaded and provided with a valve seat; a valve threaded in said casing and provided with a stem; a float-lever connected to said stem for rotating the 30 same to seat and unseat said valve; and a spring encircling said stem and connected at one end thereto and engaged at the other end with said wall, said spring being compressed by the rotation of said stem incidental to the 35 upward movement of said float-lever, whereby it will normally tend to automatically rotate said stem in the opposite direction and unseat said valve.

In testimony whereof I have hereunto set 40 my hand in presence of two subscribing witnesses.

WILLIAM E. BURKE.
